US00D532663S

(12) **United States Design Patent** (10) **Patent No.:** **US D532,663 S**
Waldron (45) **Date of Patent:** **** Nov. 28, 2006**

(54) **RANDOM ORBITAL SANDER POWER TOOL**

(75) Inventor: **Michael Waldron**, Chester le Street
(GB)

(73) Assignee: **GMCA Pty Limited (AU)**

(**) Term: **14 Years**

(21) Appl. No.: **29/222,552**

(22) Filed: **Feb. 1, 2005**

(30) **Foreign Application Priority Data**

Nov. 27, 2004 (EM) 000262282

(51) **LOC (8) Cl. 08-01**

(52) **U.S. Cl. D8/62**

(58) **Field of Classification Search** D8/67,

(57) **CLAIM**

I claim the ornamental design for a random orbital sander power tool, substantially as shown.

DESCRIPTION

FIG. 1 is a perspective view of the random orbital sander power tool.

FIG. 2 is an opposite perspective view of the random orbital sander power tool.

FIG. 3 is a side view of the random orbital sander power tool.

FIG. 4 is a top view of the random orbital sander power tool.

FIG. 5 is a bottom view of the random orbital sander power tool.

FIG. 6 is a front view of the random orbital sander power tool; and,

FIG. 7 is a rear view of the random orbital sander power tool.
